TURBINE WHEEL

Edmund Jedrzykowski, Chicago, Ill., assignor to
 International Harvester Company, a corpora-
 tion of New Jersey

Application December 13, 1946, Serial No. 716,147

7 Claims. (Cl. 253—77)

1

This invention concerns gas turbines or blowers, and relates more particularly to an improved wheel therefor with separately formed blades and means for attaching the blades to the wheel.

The general object of the invention is the provision of an improved turbine or blower wheel susceptible of production with intricately shaped blades by a method free of costly machining steps.

A more specific object is the provision of an improved turbine wheel structure wherein the shanks of separately formed turbine blades are retained within peripheral slots of the wheel by a novel arrangement of welding metal disposed within end face recess means of the wheel.

Another object is the provision of a new turbine wheel blade comprising vane and shank portions individually shaped as desired from a single piece of suitable material.

A further object is the provision of a turbine wheel having blade-receiving slots formed in the circular periphery thereof in a fashion extending between opposite end faces of the wheel and curved about individual axes extending perpendicularly to the axis of the wheel; and the invention also encompasses the process of forming these peripheral slots.

These and other desirable objects encompassed by the invention together with numerous advantages will become apparent from the ensuing description and the annexed drawings, wherein:

Fig. 1 is an end elevational view of a turbine wheel embodying features of the present invention.

Fig. 2 is a side view of the turbine wheel of Fig. 1, partly in elevation and partly in section.

Figs. 3, 4, and 5 are sectional views taken respectively on the lines 3—3, 4—4, and 5—5 of Fig. 2.

Fig. 6 is a fragmentary end elevational view of a turbine wheel structure embodying a modified form of the invention.

Fig. 7 is a fragmentary side view of the wheel structure shown in Fig. 6, partly in elevation and partly in section.

Figs. 8 and 9 are sectional views taken on the lines 8—8 and 9—9 of Fig. 7.

Fig. 10 is a fragmentary plan view looking downwardly upon the circumferential periphery of a wheel in process of having blade receiving slots formed in such periphery.

Fig. 11 is a side elevational view of the wheel and a crown saw shown in Fig. 10.

The turbine wheel structure 11 of Figs. 1 and 2 comprises a wheel proper 12 formed integrally with a shaft 13. The wheel 12 has a series of slots

2

14 formed in its circular periphery in circumferentially spaced relation. These slots extend completely between opposite end faces 15 and 16 of the wheel 12 and thereby form a series of circumferentially spaced teeth 17 upon the wheel periphery, the slots constituting spaces between said teeth. Opposite end surfaces of the teeth 17 constitute radial extensions of the opposite end faces 15 and 16 of the wheel.

10. Recess means in the form of a pair of circular recesses 18 and 19 are formed in the wheel end face 16 concentrically with the wheel axis and of such diameter that the recess means 18 intersects solely the extension portions of the face 16 upon the ends of the teeth 17 while the recess means 19 is formed partly upon the main portion of the face 16 and partly upon the radial extensions of this face carried by the ends of the teeth 17. Both of the recess means 18 and 19 communicate with the slots or spaces between the teeth 17. Recess means in the form of circular recesses 21 and 22, respectively, corresponding to the recesses 18 and 19, is formed in the opposite end of the wheel. Notches 23 are formed 20 in the outer ends of the teeth 17. These notches may be formed by a cutting tool while the wheel 12 is rotated upon a turning lathe.

Identical blades 25 are assembled in the slots 14 of the wheel 12. These blades are forged or stamped from single pieces of metal. Each blade 25 has an end portion comprising a transversely curved vane or bucket 26 and an opposite planar end portion 27 constituting a shank insertable into one of the wheel slots 14. The concave face 28 of each vane 26 is upon the obverse face of its blade, while the convex face 29 of each blade is on the reverse face of its blade. Figs. 1 and 4 illustrate that the blade shanks 27 are offset inwardly, toward the obverse faces of the blades, from the reverse faces of their blades. A dished or concavo-convex rib 31 projects rearwardly from the reverse face of each blade shank 27 and extends lengthwise of the blade as illustrated in Fig. 2 into joining relation with the associated vane 26. These ribs 31 which rigidify the blade structure are accommodated by the tooth notches 23 when the blades are assembled with the wheel proper 12.

The blade shanks are so constructed and arranged that when they are inserted into the wheel slots 14, no part of said shanks obstruct the circular recess means 18, 19, 21, and 22. This is accomplished by forming notches 32 and 33 in opposite edges of the shanks for circumferential registry with the recess means 18 and 21, and by

forming cut-away portions 34 and 35 for respective registration with the circular recess means 19 and 22. Notches 32—33 and cut-away portions 34—35 provide clearance spaces registering with the recess means 18, 19, 21, 22 and thus avoid obstructing circumferential continuity of this recess means.

While the blades are held in assembly with the wheel proper 12 by temporary means (not shown), welding metal is laid within the unobstructed grooves or recess means 18, 19, 21, and 22 and caused to establish a welded union between the sides of said recess means and the sides of the blade shank notches 32 and 33 and the sides of the blade shank cut-away portions 34 and 35. Excess welding material is ground away for causing the rings 36, 37, 38, and 39 of metal filling the recess means to present a surface flush with that of the wheel faces 15 and 16. Each of these welding metal rings is joined to the blades 25 and the outer, 36 and 38, of said rings further function as keys within the shank notches 32 and 33 for resisting the great centrifugal force exerted by these blades when the wheel structure is rotated at tremendous speed in operation.

The second form of turbine wheel structure illustrated in Figs. 6 to 11 has a wheel proper 12a corresponding to the wheel 12 of the first embodiment. The end faces of the wheel 12a contain recess means 19a and 22a corresponding to the recess means 19 and 22 in the first embodiment, and circular rings 37a and 39a of welding metal are disposed in the recess means in welding relation thereto and to cut-away portions 41 and 42 of shanks 43 of turbine blades 44.

Both the shanks 43 and buckets or vanes 45 of the blades 44 are transversely curved as illustrated in Figs. 3 and 9, the obverse faces of the blades including the concave sides of the vanes and shanks while the reverse faces of the blades include convex sides of the vanes and the shanks.

Because of the blades 44 being transversely curved throughout their length, the need for a reinforcing rib as 31 in the first embodiment is avoided. However, it is necessary for the blade shank receiving slots 46 to be curved as illustrated in Fig. 10 to conform to the blade shanks. Curved slots 46 are formed by using a crown saw or milling tool 47 as illustrated in Figs. 10 and 11. This tool is rotated about an axis $a-a$ which is spaced transversely from the axis b of the wheel 12a and is directed perpendicularly to the axis b ; see Fig. 11. This places one edge portion 48 of the circular cutter 47 substantially in radial alignment with the axis b for properly cutting the slots 46 when the wheel and cutter are moved toward one another axially of the axis $a-a$. In performing the notch cutting operations, the wheel 12a is intermittently rotated for successively carrying circular peripheral portions thereof (wherein the slots 46 are to be cut) into registry with the cutter portion 48. While each of these peripheral portions in which the slots are to be cut is in registry with the cutter portion 48, the rotating cutter and the wheel 12a are relatively moved along the axis $a-a$, first for cutting the slot and then for separating the cutter and the wheel preparatory to the succeeding indexing movement of the wheel.

Turbine wheels constructed according to the present invention need have only the blades thereof made of the costly relatively hard heat resisting metal. The wheel 12 may be made of a softer, less expensive and more easily machined metal.

In addition to the saving in material cost of the complete wheel unit 11 including the blades, the fabricating or forming operations performed upon the blades involve a minimum of machining and are otherwise relatively economical.

Having thus described a limited number of embodiments of the invention with the view of clearly and concisely illustrating the same, I claim:

1. In combination, a turbine wheel having circumferentially spaced peripheral slots communicating between opposite end faces of such wheel, said wheel also having recess means extending circumferentially of the wheel within at least one of said end faces in intersecting relation with end portions of said slots, blades associated with said slots, said blades including shanks respectively disposed in said slots and having notched edges disposed substantially flush with the end faces of said wheel, the notches of said blade shanks registering with said recess means circumferentially of the wheel, and means for anchoring said shanks in said slots comprising a ring of welding metal disposed in said recess means and in the shank notches, and said ring of metal having a weld union with the sides of said recess means and with the sides of said notches.
2. In combination, a turbine wheel having circumferentially spaced teeth projecting radially therefrom, said teeth having opposite ends constituting radial extensions of opposite end faces of said wheel, said teeth also having notches within their radial outer ends, blades for said notches, each blade having an obverse side and a reverse side, each blade having a vane at one end and a shank at the other end offset inwardly from the reverse face of its vane, and a rib on the reverse face of the shank to serve as a rigidifying connecting means between said vane and shank, said blades being assembled with the wheel by the disposal of said blade shanks respectively in the spaces between said teeth, said ribs being disposed respectively within said notches of the teeth, and means for anchoring said shanks in said assembly comprising recess means in at least one of said end faces communicative with the spaces between said teeth, and welding metal in said recess means in welded union with the side walls thereof and with the blade shanks.
3. In combination, a turbine wheel having circumferentially spaced teeth projecting radially therefrom, said teeth having opposite ends constituting radial extensions of opposite end faces of said wheel, said teeth also having notches within their radial outer ends, blades for said notches, each blade having an obverse side and a reverse side, each blade having a transversely curved vane at one end and a planar shank at the other end, the concave side of each vane being on the obverse side of its blade, and said shanks being offset inwardly from the reverse face of their associated vanes, each blade also comprising a concavo concave rib extending axially thereof along the reverse face of its shank and joining with its vane, the concave side of each rib being on the obverse side of its blade, said blades being assembled with the wheel by the disposal of said blade shanks respectively in the spaces between said teeth, said ribs being disposed respectively within said notches of the teeth, and means for anchoring said shanks in said assembly comprising recess means in at least one of said end faces communicative with the spaces between said teeth, and welding metal in said recess means in welded union with the side walls thereof and with the blade shanks.

4. A turbine blade having obverse and reverse sides, one end of said blade being transversely curved and constituting a vane of which the concave face is upon the obverse side of the blade, the other end of said blade constituting a shank offset inwardly from the reverse face of said vane, said blade also comprising a rib on the reverse face of said shank and extending lengthwise of the blade into joining relation with the vane.

5. The combination set forth in claim 4 wherein said rib is a concavo-convex structure of which the concave side forms a portion of the obverse side of said blade.

6. A turbine blade having obverse and reverse sides, an end portion of said blade being transversely curved and comprising a vane of which the concave side is upon the obverse side of said blade, the opposite end portion of said blade being substantially planar and comprising a blade shank offset inwardly from the convex side of said vane, said blade also comprising a concavo-convex rib projecting rearwardly from the reverse side of said shank and extending lengthwise of the blade into joining relation with said vane, and the concave side of said rib being a portion of the obverse face of said blade.

7. In combination, a turbine wheel having circumferentially spaced peripheral slots communicating between opposite end faces of such wheel, said wheel also having recess means extending circumferentially within at least one of said end faces in intersecting relation with ends of said slots, blades associated with said slots, said blades having shanks respectively disposed in said slots, said blade shanks having opposite edges re-

spectively in flush relation with the wheel end faces, said blade shanks having notch-forming surface portions within the edge thereof at said end of the wheel and forming boundaries for portions of said recess means, and means for anchoring said shanks in said slots comprising a ring of welding metal disposed in said recess means where said ring has a weld union with the end face of the wheel, and said ring extending continuously across and through the notches in the edges of the blade shanks where such ring has a weld union with said surface portions of the blade shanks.
